(57) CLAIM

The ornamental design for a trouser stocking, as shown and described.

DESCRIPTION

FIG. 1 is a front view of a trouser stocking showing my new design;

FIG. 2 is a partial enlarged detail view of a portion of the trouser stocking;

FIG. 3 is a back view of the trouser stocking;

FIG. 4 is a side perspective view of the trouser stocking;

FIG. 5 is a another partial enlarged detail view of a portion of the trouser stocking; and,

FIG. 6 is an opposite side perspective view of the trouser stocking.

The broken lines in the drawings depict feature lines of the trouser stocking that form no part of the claimed design.

1 Claim, 5 Drawing Sheets
